(57) CLAIM

The ornamental design for a digital audio player, as shown and described.

DESCRIPTION

FIG. 1 is a perspective view of digital audio player showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines are for illustrative purposes only and form no part of the claimed design.
